UNITED STATES PATENT OFFICE.

MAX H. MISFELDT, OF MALTA, MONTANA, ASSIGNOR OF ONE-HALF TO GUSTAV F. THOMPSON, OF MALTA, MONTANA.

OIL-CAN.

1,293,859.

Specification of Letters Patent. Patented Feb. 11, 1919.

Application filed April 27, 1918. Serial No. 231,126.

To all whom it may concern:

Be it known that I, MAX H. MISFELDT, a citizen of the United States, residing at Malta, in the county of Phillips and State of Montana, have invented certain new and useful Improvements in Oil-Cans; and I do hereby declare the following to be a full, clear, and exact description of the invention, such as will enable others skilled in the art to which it appertains to make and use the same.

My invention relates to oil cans, and has for its object to provide an extremely simple and highly efficient means for normally closing the spout thereof to prevent the contents in the can from spilling in case said can is upset.

To the above end, the invention consists of the novel devices and combinations of devices hereinafter described and defined in the claim.

The invention is illustrated in the single sectional view in the accompanying drawing.

The numeral 1 indicates an oil can having a screw cover 2, to which is secured a spout 3, with a curved outer end. The inner end of the spout 3 is extended slightly inward of the inner face of the cover 2 and affords a valve seat 4. Formed with the spout 3 near the inner end thereof and on the opposite side thereof from the direction in which the outer end of said spout is curved, is an oblique nipple 5, which extends upwardly and outwardly with respect to said spout and affords a valve stem seat or guide.

Normally, the spout 3 is closed by a disk valve 6, which is held against the seat 4, as will presently appear. This valve 6 is provided with an oblique stem 7, which extends through the nipple 5 and has, on its outer end, a finger piece 8. A coiled spring 9, encircling the valve stem 7 and com-

pressed between the nipple 5 and finger piece 8, normally holds the valve 6 against the seat 4. A pliable gasket 10 is placed upon the upper face of the valve 6 to afford a tight joint between said valve and the seat 4.

To prevent the valve stem 7 from turning in the nipple 5, the same is provided with a key 11, which works in a keyway formed in said nipple. Any other suitable means, of course, may be provided to accomplish this same result. As previously stated, the spring 9 yieldingly holds the valve 6 closed and thereby prevents the contents of the can 1 from spilling in case the oil can is upset. By pressing downward on the finger piece 8, against the tension of the spring 9, the valve 6 may be opened at will, to permit a discharge of the contents in the can through the spout 7 by the customary movement of the bottom of said can. As soon as the finger piece 8 is released the spring 9 will immediately close the valve 6. The improved oil can is well adapted to be carried in the tool boxes of automobiles or placed where the same is liable to be upset.

What I claim is:

An oil can having a discharge spout with an oblique nipple affording a valve stem seat, a valve arranged to seat against the inner end of said spout and close the same, said valve having an oblique stem working in said nipple, a finger piece on the outer end of said stem, and a coiled spring encircling the valve stem and compressed between said finger piece and nipple.

In testimony whereof I affix my signature in presence of two witnesses.

MAX H. MISFELDT.
